US0D1021791S

(12) **United States Design Patent** (10) Patent No.: **US D1,021,791 S**
(45) Date of Patent: ** Apr. 9, 2024

(54) **DOCKING STATION FOR CLEANING ROBOT**

(71) Applicant: **Beijing Roborock Technology Co., Ltd.**, Beijing (CN)

(72) Inventors: **Zhenyu Liang**, Beijing (CN); **Fanwei Meng**, Beijing (CN); **Zechen Yu**, Beijing (CN)

(73) Assignee: **Beijing Roborock Technology Co., Ltd.**, Beijing (CN)

(**) Term: **15 Years**

(21) Appl. No.: **35/513,972**

(22) Filed: **Dec. 28, 2021**

(80) **Hague Agreement Data**

Int. Filing Date: **Dec. 28, 2021**

Int. Reg. No.: **DM/219753**

Int. Reg. Date: **Dec. 28, 2021**

Int. Reg. Pub. Date: **Apr. 8, 2022**

(30) **Foreign Application Priority Data**

(57) **CLAIM**

The ornamental design for a docking station for cleaning robot, as shown and described.

DESCRIPTION

Fig. 2.1 is a front view of a docking station for cleaning robot;

2.2 is a back view thereof;

2.3 is a left view thereof;

2.4 is a right view thereof;

2.5 is a top view thereof;

2.6 is a bottom view thereof;

2.7 is a front, left perspective view thereof;

2.8 is a back, left perspective view thereof; and

2.9 is a right, bottom perspective view thereof.

The broken lines in the reproductions depict portions of the docking station for cleaning robot that form no part of the claimed design.

1 Claim, 9 Drawing Sheets
